UNITED STATES PATENT OFFICE.

RANDOLPH F. HALL, OF ITHACA, NEW YORK.

AIRPLANE.

Application filed December 8, 1926. Serial No. 153,326.

This invention relates to certain improvements in air planes; and the nature and objects of the invention will be readily recognized and understood by those skilled in the arts involved in the light of the following explanation and detailed description of the accompanying drawings illustrating what I, at present, consider to be the preferred embodiments or mechanical and aerodynamical expressions thereof from among various other forms, arrangements, combinations and constructions of which the invention is capable within the spirit and scope thereof.

Where high speed and increased performance are required from air craft, the cross sectional area of air craft bodies are frequently reduced with the consequent sacrifice of comfort to occupants thereof and reduction in their efficiency in using and operating apparatus carried thereby. This reduction in cross sectional area or depth of air craft bodies is encountered particularly with such craft designed for military purposes, that is, so-called service air craft. With air craft bodies of reduced cross sectional area or depth and mounting guns or other ordnance or apparatus for operation by an operator within the body, such operator is necessarily exposed and seriously restricted and hampered in the operation of his guns or other apparatus to such an extent as to seriously detract from the efficiency and value of such types of air craft bodies.

A primary object of the present invention is to eliminate and materially reduce the above disadvantages arising from air craft bodies of small cross sectional area or depth, by providing a design and arrangement of the body, whereby additional depth can be given the same for use by the gunner or operator during use of the guns or other apparatus in flight, and the original depth restored upon completion of such use, in order to retain and secure normal designed performance from the body. A further object of the invention is to provide for a projectable and retractable gunner's compartment for air craft bodies in order to increase the depth thereof at the gunner's station or cockpit to enable the gunner to be protected from the air stream and operate his guns or other apparatus without being hampered or interfered with by the wind pressure, as well as for increasing the depth and capacity of a cockpit for other purposes. A further object of the invention is to provide an efficient

mounting for such a projectable and retractable compartment together with mechanically simple and efficient operating mechanism for the compartment readily accessible to an occupant.

A further object resides in a design and construction of projectable and retractable gunner's compartment which will have a high factor of safety and can be embodied in air craft bodies without weakening or otherwise impairing the operation and function of such bodies.

With the foregoing and certain other objects and results in view, which other objects will be readily apparent to those skilled in the art from the following explanation, the invention consists in certain novel features in construction and in combinations and in arrangements of elements as will be more fully and particularly referred to and specified hereinafter.

Referring to the accompanying drawings in which similar reference characters referred to corresponding parts throughout the several figures thereof:

Fig. 1 is a longitudinal vertical section through a portion of an air plane fuselage embodying the projectable and retractable compartment of the invention.

Fig. 2 is a top plan view of Fig. 1 showing the gun mount and gunner's cockpit with the compartment of the invention therein.

Fig. 3 is a detailed vertical section through a portion of the compartment showing the mounting, therefore, and the operating mechanism by which the compartment is projected and retracted.

A possible embodiment and adaptation of a projectable and retractable compartment of the invention is disclosed in the accompanying drawings and described herewith as mounted on and installed in the fuselage or body of an air-plane in cooperation with a cockpit or gunner's station. However, the illustrated embodiment and its adaptation and installation is shown merely by way of example and not of limitation, in order to present the principles and various features of the invention for purposes of explanation to enable those skilled in the aeronautical art to understand the same. Obviously, the broad principles and features of the invention are capable of a wide variety of mechanical and aero-dynamical expression, as well as adaptation to and installation on and with air craft elements generally of the body

types, among which may be mentioned nacelles, wings of the thick section type, pontoons, and the like, where similar or equivalent conditions are present and the 5 advantages and results from the use of the invention may be desired.

The example of the invention presented herein is shown as applied to and embodied in an air plane fuselage 10 of the usual or any 10 other desired type in which, for purposes of speed and performance, the cross sectional area or depth of the fuselage or body, is relatively small or reduced. The fuselage 10 is provided with the usual cockpit or gunner's 15 station 11, opening through the upper or top wall of the fuselage and having the gun mount of the ring type 12 mounted on and around the cockpit opening so that a gunner stationed in the cockpit is located and stands 20 within the gun mount for operating a gun carried thereby, as will be familiar to those skilled in this art. With a fuselage 10 of the reduced cross sectional area or small depth, experience has shown that the gunner in 25 standing in the cockpit for operation of a gun or other apparatus, is too greatly exposed to air pressures for efficient operation of his gun, so that the aero dynamical advantages from the small cross sectional area or reduced 30 depth type of fuselage, are greatly offset and impaired by this operating disadvantage for the gunner in flight.

According to the present invention, the example presented herewith, the fuselage 10 embodies the lower wall or bottom 14 and a gunner's upper floor or walk 15 spaced above the bottom of the fuselage and extending longitudinally thereof across and beneath the cockpit 11, and the upper opening thereof 40 with the gun mount 12. If desired, the gunner's floor 15 can terminate at one side of the cockpit in the upturned end portion 15'. The gunner's floor 15 is provided and formed with an opening 16 therethrough below and 45 in line with the upper cockpit opening and the gun mount 12, as will be readily apparent from Figs. 1 and 3 of the accompanying drawings.

In the lower wall or bottom 14 of the fuselage 10, an opening is formed beneath, and in line with the opening 16 in the gunner's floor 15, and a series of supporting and guiding columns or rods 17 are fixed in vertically disposed position between the bottom wall 14 50 and the gunner's floor 15, with these columns or rods 17, depending outwardly and downwardly a distance below and beneath the bottom 14 of the fuselage 10.

The columns or rods 17 form supports and 60 guides for a gunner's floor compartment which is normally disposed retracted within the fuselage 10 between, and forming a part of the bottom wall 14, and the gunner's fixed floor 15. In the example hereof, this gunner's 65 floor compartment 18 is in the form of an

open top shell or casing having the bottom wall 19 providing the floor for receiving and upon which a gunner or other occupant of the cockpit 11, stands. The floor compartment 18 is mounted beneath the fixed gunner's floor 15 between the upper ends of the columns 17 within the fuselage 10 and having its bottom wall or floor 19 forming a portion of the bottom wall 14 of the fuselage and occupying and substantially closing the space or opening formed through wall 14 beneath the floor opening 16. Supporting bearings 20 are fixed to and carried by the upper end of the compartment 18, projecting laterally therefrom and fitting over and slidably received by the supporting and guiding columns 17, respectively. Lower supporting bearings 21 are fixed to and extend laterally from the lower end of the compartment 19 and receive and slidably fit over the depending portions of the columns or rods 17, beneath and on the exterior of the bottom wall 14 of fuselage 10. Thus the gunner's floor compartment 18 is supported on and between the column 17 and is slidable longitudinally thereon inwardly and outwardly, to and from retracted and projected position with respect to the fuselage 10. Coiled expansion springs 22, are mounted on rods or columns 17 within the fuselage 10 between the upper supporting 95 bearings 20 of the compartment, and the bottom wall 14 of the fuselage. These springs 22, normally retract the gunner's compartment to position within the fuselage as shown by Figs. 1 and 3 of the drawings.

From normal retracted position the gunner's floor compartment 18, is slidable or projectable outwardly on rods 17 against the tension of coiled springs 22, to a position extending outwardly from and downwardly below the fuselage, such as indicated in dotted outline in Fig. 3. The outer ends of rods 17 are provided with the adjustable stop members 23 for engaging the supporting bearings 21 of the gunner's compartment and these stops 23 are provided with suitable shock absorbers or pads 24, which can be formed of rubber of any other desired material, to lessen the jar of impact between bearings 21 and the stops when the compartment is projected. The adjustable stops 23 can be in the form of a headed shank or plug extending upwardly into the rods 17 with a suitable series of spaced bores through the shanks of the stops and the rods 17, for receiving a removable pin 26 110 to hold the stops in the desired adjusted position, all of which is clearly indicated and shown by Fig. 3 of the drawings.

Suitable mechanism is provided for holding and securing the floor compartment 18, retracted and in projected positions. A possible mechanical expression of such mechanism is disclosed herewith and particularly in Fig. 3 of the drawings to which reference is now had. A lever 27 is pivotally mounted at 125

to one of the lower supporting bearings 21, preferably the forward one, and this lever extends upwardly a distance into the compartment 18 through a suitable opening in the bottom wall or floor 19 thereof. This lever 27 is provided with a finger 29, extending forwardly and outwardly from the pivot 28 to the adjacent column or rod 17 for engagement with the wall thereof. the general characteristics of an air craft body, and with which elements it may be desired to employ a gunner's compartment embodying the principles of the invention.

5 It is also evident that various other changes, variations, modifications and substitutions might be resorted to without parting from the spirit and scope of my invention, and hence I do not wish to limit myself 10 to the exact and specific disclosures hereof.

Desiring to protect my invention in the broadest manner legally possible, what I claim and desire to secure by Letters Patent of the United States, is:

15 1. In an aircraft body having a cockpit therein, a compartment within the cockpit and projectable outwardly from the body to increase the cockpit depth, said compartment retractable to normal position within the body, and foot controlled means for locking the compartment in projected and retracted positions, said means operable from the compartment by the foot of an occupant therein.

20 2. In an aircraft body having a cockpit therein, an equipment mount at the upper end of the cockpit, a floor compartment at the lower end of the cockpit, the said compartment projectable outwardly to increase the cross sectional area of the body, and retractable 25 inwardly to normal position within the cockpit unobstructing the same laterally and upwardly to permit of operation of said mount.

30 3. In an aircraft body having a cockpit therein, a floor within the body spaced above the lower wall thereof extending across the cockpit, and an open top projectable floor compartment between the lower wall and body floor within the cockpit, said floor open 35 above said floor compartment.

40 4. In an aircraft body having a cockpit therein, a floor within the body spaced above the lower wall thereof extending across the cockpit, an open top floor compartment within the cockpit between the body lower wall

and floor with the compartment forming a 45 portion of the body lower wall, said floor having an opening therethrough within the cockpit above the floor compartment and said compartment projectable outwardly from the body to increase the cockpit depth, and retractable to normal position within the body. 50

5. In an aircraft body having a cockpit therein, a floor compartment forming the bottom wall of the cockpit and projectable outwardly from the body to increase the cockpit depth, said compartment retractable to normal position within the body, means for locking the compartment in projected and retracted positions, a foot controlled member accessible from within the compartment for actuating said locking means, and guard means for said foot controlled member to prevent accidental operation thereof by the foot of an occupant of the compartment. 55

6. In an aircraft body having a cockpit therein, a floor within the body spaced above the lower wall thereof extending to the cockpit, an open top floor compartment within the cockpit between the lower body wall and floor with the compartment forming a portion of the body lower wall, members in the body spaced around the compartment and depending downwardly through the body, outwardly a distance beyond the body wall, said compartment slidably mounted on and 70 carried by said members, expansion springs on said members between the body wall and inner end mounting of said compartment on the members, the said compartment projectable outwardly from the body on said members against the tension of said springs and retractable inwardly to normal position by the action of the springs, and means for locking said compartment in projected and retracted positions. 75

Signed at Ithaca, New York, this 2nd day of December, 1926.

RANDOLPH F. HALL.
